(57) **CLAIM**

The ornamental design for a counter-top organizer for pot lids and utensils, as shown and described.

DESCRIPTION

FIG. 1 is a perspective view of a counter-top organizer for pot lids and utensils showing my new design;

FIG. 2 is a front elevation view thereof;

FIG. 3 is a rear elevation view thereof;

FIG. 4 is a right side elevation view thereof, the left side being a mirror image;

FIG. 5 is a top plan view thereof; and,

FIG. 6 is a bottom plan view thereof.

The broken line showing of environmental structure is for illustrative purposes only and forms no part of the claimed design.
